UNITED STATES PATENT OFFICE.

WILLARD IRVING TWOMBLY, OF NEW YORK, N. Y.

INTERNAL-COMBUSTION ENGINE.

1,113,262.

Specification of Letters Patent.

Patented Oct. 13, 1914.

Application filed February 16, 1911. Serial No. 608,889.

To all whom it may concern:

Be it known that I, WILLARD IRVING TWOMBLY, a citizen of the United States, residing in the borough of Manhattan, in the city, county, and State of New York, have invented new and useful Improvements in Internal-Combustion Engines, of which the following is a specification.

This invention relates to internal combustion engines in which mechanical power is derived from heat due to the combustion of an explosive mixture within a chamber, and relates particularly to this class of engines of the "two cycle" type, in which, during a single revolution of a power shaft, a combustible mixture or fuel is compressed by a piston in a chamber, a power stroke imparted to the piston as a result of the combustion of said compressed fuel, the exhaust of the burnt or spent gases of combustion from the chamber, and the supplying of a fresh charge of combustible mixture or fuel to the chamber.

It is the principal object of the invention to provide an engine of this type that is novel and simple in construction, durable and highly efficient in operation. In carrying out the object of the invention I provide a rotatable shaft having a single crank and dispose adjacent to said shaft piston cylinders having fuel-intake and exhaust ports with the axes of the cylinders parallel with the axis of said shaft, pistons being fulcrumed to oscillate in the respective cylinders, and the respective pistons having a crank-and-link connection with the crank of the rotatable shaft, whereby to convert the oscillatory motions of the pistons into continuous rotary motion of the shaft. The cylinders are provided with a head or partition whereby to separate or divide them into fuel-pumping and combustion chambers, a by-pass port in the pistons opening and cutting off communication between the said chambers during a cycle of operation.

A further object of the invention relates to means for mechanically air cooling the engine.

In the drawings accompanying and forming a part of this specification, Figure 1 is a plan view of my improved engine. Fig. 2 is a front end elevation taken on the line A—A of Fig. 1. Fig. 3 is a cross sectional plan view taken substantially midway through Fig. 1, the piston being removed from the cylinder at the left. Fig. 4 is a

sectional end elevation of the piston cylinders, the section being taken substantially on the line C—C of Fig. 3, with the end removed from the cylinder at the left to illustrate the piston therein. Figs. 5, 6 and 7 are diagrammatic views to illustrate the different positions of the pistons in the cylinders and of the crank-and-link connection between the pistons and rotatable shaft. Fig. 8 is a front elevation of one of the pistons. Fig. 9 is an end elevation of a piston looking toward the right of Fig. 8 with the piston packing removed. Fig. 10 is a detail to illustrate the sliding joint or dovetail connection of the ends of the piston packing. Fig. 11 is a detail of the piston packing connection looking at the left of Fig. 10. Fig. 12 is a detail of the piston packing at the heads of the pistons. Fig. 13 is a detail of the piston packing at the ends of the pistons; and Fig. 14 is a cross sectional view of the crank case, piston cylinders and pistons taken on the line B—B of Fig. 3.

Similar characters of reference designate like parts throughout the different views of the drawings.

In the drawings I have shown my improved engine constructed as being particularly adapted for use in connection with motor vehicles to be readily and quickly removed therefrom, although it will be obvious that the same may be utilized for any purpose for which an engine of this character is adapted.

The embodiment of my invention illustrated in the drawings comprises a central crank case 1, having separate chambers 2, 2, at opposite sides thereof with piston cylinders a, b, adjacent to said chambers, which may be constructed integral with the case or separate therefrom and secured thereto, the piston cylinders communicate with the chambers 2, 2, by means of ports 4, 4. The cylinders a, b, are in the form of cylindrical drums having laterally projecting cooling fins 5 and removable ends 6, 6', each cylinder has a fuel-intake port 7 in the cylindrical wall communicating with ducts 8 in the crank case having an inlet 9 connected with the source of fuel supply. The cylinders are also provided with exhaust ports 10 communicating with exhaust pipes 11 secured to the cylinders in any suitable manner.

A rotatable shaft 12 is journaled by means of ball bearings in the crank case 1,

said shaft having a crank 13 and crank pin 14, in the present instance at one end and outside of the case. A fly-wheel F is keyed to the other end of the shaft 12 and secured by a nut 15, a ball thrust bearing being interposed between the hub of the wheel and the crank case. The said fly-wheel may also serve as a friction drive wheel. It will be noted that the crank case is hollow and may 5 contain a suitable lubricant whereby to lubricate the shaft bearings, the plates 16, 16 to retain the ball bearings in place preventing any oozing out or dripping of lubricant. The axes of the piston cylinders are parallel 10 with the axis of the rotatable shaft but in a different plane, in the present instance above the same, for a purpose to be herein-after described.

As already stated, the present engine is 20 designed to be particularly applicable for use in motor vehicles, and for this purpose it is provided with hanger arms 17 projecting laterally from the cylinders and having rollers mounted on the outer extremities 25 whereby the engine may be rolled into and out of the chassis frame and supported therein, suitable means being provided to limit the inward movement of the engine and maintain it in rigid position on the 30 chassis frame, a plate 18 extending across and releasably secured to the front of the chassis frame maintaining the engine therein.

Pistons c, d, (Figs. 8 and 9) in the form 35 of segmental trunk pistons, rectangular in cross section in the present instance, are provided for the respective cylinders a, b, the said pistons having a hollow hub portion 19 with laterally projecting trunnions 20, 21 whereby they are fulcrumed in the cylinder 40 ends 6, 6' by means of ball bearings 22 carried in bosses or housings 23 projecting laterally from the cylinder ends, the ball bearings being retained in said housings by releasable caps 24, 24'. The caps 24 have an 45 opening to register with the openings in the piston hubs. The piston trunnions 21 project through the bearing-retaining plates 24' and have a reduced tapered portion, as at 25. A crank 26 having a crank pin is fixed 50 to the reduced portion 25 of the trunnions 21 of the respective pistons, the said cranks abutting against the shoulder formed by the reduced portion 25 and secured in place by nuts 27. The crank pins of the respective 55 cranks 26 are connected to the crank pin 14 of the rotatable shaft by connecting rods or links 28, 28. The said rods are mounted on the pins of the cranks 26 and the crank pin 14 by means of ball bearings, although this 60 is not essential as the rods may be connected directly to the crank pins or by any suitable bushings.

The pistons have grooves or recesses 29 65 extending transversely of the side and outer walls near the heads and ends for the recep-

tion of packing 30, the packing at the heads consisting (as shown in Fig. 12) of movable splines of some suitable metal, such as cast iron, to fit in the grooves so that they will slightly project beyond the outer surfaces of the pistons. The said splines have saw cuts 70 extending from the ends to substantially midway thereof and concaved on that side engaging within the piston grooves, as at 31, and tapered on the same surface toward the 75 outer ends. By this construction the splines can be made of a thickness to project slightly out from the grooves, but when the pistons are placed in the cylinders the splines may be slightly sprung so that they will be substantially flush with the surface of the pistons 80 and the latter readily placed in position in the cylinders, the resilient action of the metal of the splines when the pistons are in the cylinders always keeping the packing in firm contact with the walls of the cylinders 85 to effectively seal the pistons. The ends of the packing extending across the outer wall of the pistons have a sliding joint or dovetail connection with the ends of the packing 90 extending transversely of the sides, as clearly shown in Figs. 10 and 11.

The packing at the ends of the pistons consists of splines 32, preferably of cast iron, to slidably fit in the piston grooves, but of 95 a thickness less than the depth of the piston grooves, flat or leaf springs 32' being interposed between said splines and the bottom of the grooves to force the packing out against the walls of the cylinders. The ends of 100 these splines extending across the outer wall of the pistons also have a sliding joint or dovetail connection with the ends of the splines extending transversely of the sides, the same as the packing at the heads of the 105 pistons.

To place the pistons in the cylinders one of the ends of the cylinders is secured in place, the piston with its packing is then placed in the cylinder with the piston trunnion 20 engaging in its journal in the secured cylinder end, when the other cylinder end is secured in place. Each of the cylinders has a head or partition 33 releasably secured therein by bolts or screws 34, the said 110 heads extending from the walls of the cylinders to the hubs of the pistons and for the entire length of the cylinders. These heads when the pistons are in the cylinders separate or divide the latter so that the 115 space between the ends of the pistons and the heads in connection with the chambers 2, 2, will constitute fuel pumping and compression chambers e, and the space between the heads of the pistons and said partitions 33 will constitute combustion chambers f, as 120 clearly shown in Fig. 14. The chambers e, are always in communication with the chambers 2 by means of the ports 4 to relieve the 125 said chambers e of any high fuel compres- 126

sion pressures. The fuel-intake ports 7 also communicate with the chambers *e*. To conduct or lead the compressed fuel from the chambers *e* to the chambers *f* the hubs of the pistons are constructed with by-pass ports 35 which coöperate with the heads 33 to open up and cut off communication between the respective chambers. To effectively seal the fuel pumping and compression chambers *e* from the combustion chambers *f* as the fuel is being compressed in the latter chambers previous to combustion, I provide packing comprising a slidably mounted spline 36 (of the construction shown in Fig. 12) in a recess or groove extending the length of the heads 33, the said splines normally bearing against the piston hubs, but when the pistons are in position with the by-pass ports adjacent to said splines and opening communication between the fuel-pumping and combustion chambers *e*, *f*, the splines will bear at their ends upon the piston hubs and midway thereof against a rib in the by-pass port 35.

For the purpose of facilitating the air cooling of the engine, I secure vanes or blades 37 to the back of the fly-wheel *F*, and provide air deflectors 38 to extend around the cylinder fins, the said deflectors projecting beyond the cylinders toward the fly-wheel vanes 37. The vanes as the fly-wheel revolves draw the heated air away from the cylinders and from between the deflectors and cylinder-fins, as well as through the hollow piston hubs, and throw it outwardly therefrom. The heads or partitions 33 may also be provided with openings extending through the length thereof and air drawn through said openings by the vanes 37 to materially aid in cooling the same. To increase the sucking action of the vanes 37 to draw the heated air away from the engine toward the center of the fly-wheel an annular member or plate 38' may be secured to the engine to extend around the projecting ends of the deflectors, the said plate having openings to register with the space between the deflectors and the cylinder fins.

For the purpose of further materially facilitating the mechanical air cooling of the engine, I provide rotatable fans 39 comprising blades or vanes fixed to wheels 40 having a beveled friction face and rotatably carried on studs secured in the retaining plate or bar 18. The said fans are frictionally driven by a wheel 41 mounted to rotate with and have sliding movement on the pin of a crank 42 fixed to the pin 14 of the crank 13 of the rotatable shaft and extending parallel with said crank 13, the said pin of the crank 42 projecting through the wheel 41 and journaled in a socket in the end of a starting crank 43 rotatively mounted in the plate 18 and a bushing 44 connected to

said plate. The pin of the crank 42 is provided with oppositely-disposed pins 45 adapted to engage in notches or serrations in the end of the starting crank 43 but normally maintained out of engagement therewith by a spring 45 enclosed by the bushing 44 and confined between the plate 18 and an annular flange on the crank 43. The said wheel 41 may be provided with a suitable friction material, in the present instance comprising an annular member 46 secured to the said wheel and having a beveled friction face to engage with the beveled face of the fan wheels 40 to drive the latter. As already stated the wheel 41 is slidably mounted on the pin of the crank 42 and for the purpose of maintaining said wheel in frictional engagement with the fan wheels 42 I provide a spring 47 carried by the crank pin 14 outside of the crank 42, the said spring 47 being forked to engage with the face of the wheel 41 at opposite sides of the pin of the crank 42. By this construction when the plate 18 is removed for the purpose of taking the motor from the chassis frame, the fan wheels 40 carried by said plate will readily pull away from the friction face of the wheel 41, and as readily re-engage therewith when the plate is replaced, the spring 47 taking up any play between the wheels 40 and 41 and maintaining the wheels in frictional engagement.

The operation of my improved engine is substantially as follows: Assuming the shaft 12 to be rotating in the direction of the arrow with the pistons *c*, *d*, in the positions indicated in Figs. 7 and 14, an explosion or combustion of fuel having taken place in the combustion chamber *f* of cylinder *a* and a power stroke imparted to the piston *c* in the direction of the arrow, the burnt gases exhausting from the port 10, and the fuel compressed in the chamber *e* during the power stroke entering into chamber *f* by way of the by-pass port 35, a deflector (Fig. 14) comprising a plate 50 secured to the head 33 and spaced apart therefrom by spacers 51, directing the incoming fuel through the port 35 to the outer wall of the chamber *f* where it will mushroom in such manner as to thoroughly expel the burnt gases from said chamber through the exhaust port 10. The piston has had an oscillatory movement of approximately 130 degrees and imparted a rotary motion of 180 degrees to the shaft 12. During this movement of the piston *c*, piston *d* has been compressing a previously injected charge of fuel in the combustion chamber *f* of cylinder *b*, and is at the end of its compression stroke. During this movement of the piston *d* a vacuum is created at the end thereof and in the adjacent chamber 2, and when the piston *d* is at the end of its stroke in the chamber *f* with the inlet port 7 uncovered (as shown) a fresh

supply of fuel is sucked or drawn into the chamber *e*. The pistons *c*, *d*, are now in the positions shown in Fig. 7 with the exhaust port 10 of cylinder *a* uncovered exhausting the burnt gases from the chamber *f* and simultaneously therewith admitting a fresh charge of compressed fuel from chamber *e* through the by-pass port 35. The piston *d* in cylinder *b* has compressed a charge of fuel 5 in the combustion chamber *f*, the fuel-intake port 7 of chamber *e* being open, and a fresh charge of fuel entering said chamber. The compressed charge in chamber *f* of cylinder *b* is now ignited by an electric spark generated 10 by a spark plug 53 connected to a magneto 54 carried on the top of the crank case, and gear driven from shaft 12. (Figs. 1, 2 and 14.) As the combustion of fuel in chamber *f* of cylinder *b* takes place, an oscillatory power stroke in the direction of the arrow, and reverse to the power stroke of the piston *c*, will be imparted to the piston *d*, oscillating said piston approximately 130 degrees and imparting to the shaft 12 a further rotary motion of 180 degrees, and the piston *c* will be oscillated in a reverse direction by shaft 12. 15

During the initial portion of the power stroke of piston *d* and the return movement 20 of the piston *c*, the fuel-intake and exhaust ports in both cylinders will be closed, and the chambers *e*, *f*, have no communication with each other by way of the by-pass ports 35, (as shown in Fig. 5,) the piston *c* compressing a charge of fuel in combustion chamber *f* of cylinder *a* previous to ignition, and the piston *d* compressing fuel in the pumping chamber *e* previous to being injected into combustion chamber *f* of cylinder 25 *b*. As the piston *d* approaches the end of its power stroke, the exhaust port 10 will begin to uncover and the said chamber *f* relieved of the high pressures of the products of combustion through the exhaust port 30 10. Just after said exhaust port has begun to be uncovered by the piston *d*, the by-pass port 35 will begin to open communication between the chambers *e*, *f*, and the charge of fuel previously compressed in the pumping 35 chamber *e* will rush through the port 35 and be directed by the deflector 50 to the outer walls of the cylinder for the purpose as already described in connection with the operation of piston *c* in cylinder *a*. The pistons 40 are now in the positions indicated in Fig. 6 with the compressed charge in the combustion chamber *f* of cylinder *a* to be ignited by an electric spark generated by the spark plug 53 when the operations just described 45 will be repeated.

From the foregoing description it will be noted that when a power stroke is imparted to one of the pistons the other piston is compressing a charge of fuel in the combustion 50 chamber, and that there will be two impulses

imparted to the rotatable shaft to each revolution thereof. Furthermore, when one of the pistons is at the end of its power stroke the other piston is at the end of the fuel-compressing stroke, and they will be in either one of the positions illustrated in Figs. 6 or 7 and that the centers of the piston crank pins 25, the crank pin 14, and the rotatable shaft will be in alinement or in a dead-center position at one side of the axes 70 of the pistons, the impetus of the fly-wheel *F* carrying the wrist-pin 14 over the dead-center position. The connection of the pistons with the shaft 12 is in the nature of a toggle-joint the dead-center position of 75 which is overcome or broken by the impetus of the fly-wheel. This dead-center position of the piston-crank pins, the pin 14 and the power shaft is due to the locating of the pistons with their axes in a plain different than, 80 in the present instance above, the axis of the power shaft and obviates any liability of the pistons overthrowing. Owing to the locating of the axes of the pistons relative to the axis of the power shaft as shown, and 85 the crank and link connection of the pistons and said shaft, the pistons will have a quick movement imparted thereto during the initial portion of the power stroke, or just subsequent to the ignition of a compressed fuel charge with a consequent rapid expansion of the fuel mixture, increasing the power efficiency thereof and imparting a quick and powerful impulse to the shaft 12; and that 90 a slow movement will be imparted to said 100 pistons during the latter portion of the compression stroke with a consequent slow compression of the combustible mixture.

Variations may be resorted to within the scope of my invention and portions of the 105 invention may be used without others.

Having thus described my invention, I claim:

1. In an internal combustion engine, the combination of a rotatable shaft; a cylinder 110 adjacent to said shaft; fuel-intake and exhaust ports in the cylindrical walls thereof, a piston fulcrumed to oscillate in the cylinder controlling the opening and closing of the ports and connected to the shaft; and 115 fixed means in the cylinder coöperating with the piston to separate the cylinder into fuel-pumping and combustion chambers.

2. In an internal combustion engine, the combination of a rotatable shaft; a cylinder 120 adjacent to said shaft; fuel-intake and exhaust ports in the cylindrical walls thereof, a piston fulcrumed to oscillate in the cylinder controlling the opening and closing of the ports and connected to the shaft; and 125 means in the cylinder coöperating with the piston to separate the cylinder into a pair of chambers and a fuel-pumping chamber at one end of the piston and the other a combustion chamber at the other end of the pis- 130

ton, comprising a fixed head extending between the walls of the cylinder and fulcrum of the piston.

3. In an internal combustion engine, the combination of a rotatable shaft; a cylinder adjacent to said shaft; fuel-intake and exhaust ports in said cylinder, a piston to oscillate in the cylinder controlling the opening and closing of the ports and connected to the shaft; a fixed head in the cylinder, said head coöperating with the piston to separate the cylinder into fuel-pumping and combustion chambers; and a port in the piston controlled by the head to open and cut off oil communication between the fuel-pumping and combustion chambers at predetermined points in the oscillations of the piston.

4. In an internal combustion engine, the combination of a rotatable shaft having a crank; a piston chamber comprising a cylindrical drum located adjacent to said shaft; fuel-intake and exhaust ports in the cylindrical wall thereof; a segmental trunk piston having a hub portion with laterally-projecting trunnions whereby it is journaled in the ends of the drum to oscillate therein and controlling the opening and closing of the ports; a head in the piston chamber extending from the walls thereof to the piston and coöperating with one end of the piston to provide a fuel pumping chamber in the cylinder and with the other end of the piston to provide a combustion chamber in the cylinder; a crank fixed to one of the trunnions of the piston; and a connecting rod to connect the piston crank with the crank of the shaft.

5. In an internal combustion engine, the combination of a rotatable shaft having a crank; a cylindrical drum adjacent to said shaft; fuel-intake and exhaust ports in said drum, a piston to oscillate in said drum connected to the crank of the shaft; a head in the drum, said head with the piston separating the drum into two separate chambers, one of which constitutes a combination chamber and the other a fuel pumping and compression chamber; and means to open and cut off communication between the combustion and fuel-pumping chambers at predetermined points in the oscillations of the piston.

6. In an internal combustion engine, the combination with a rotatable shaft having a crank and crank pin; a pair of piston chambers comprising cylindrical drums located at opposite sides of and adjacent to said shaft; fuel-intake and exhaust ports in the cylindrical walls of said chambers; segmental trunk pistons for the respective chambers fulcrumed to oscillate therein and controlling the opening and closing of the ports; a head in each cylinder with which the pistons coöperate to divide the cylinders into fuel pumping and combustion

chambers; a crank having a crank pin carried by each of the pistons; and connecting rods to connect the piston crank pins to the crank pin of the rotatable shaft, so that when one piston is at the end of its power stroke, the other piston will be at the end of its fuel-compression stroke.

7. In an internal combustion engine, the combination of a rotatable shaft having a crank and crank pin; a pair of cylinders one located at each side of and adjacent to said shaft; fuel-intake and exhaust ports in said cylinders; pistons fulcrumed to oscillate in the respective cylinders and controlling the opening and closing of the ports; a head in each cylinder with which the pistons coöperate to divide the cylinders into fuel pumping and combustion chambers; a crank having a crank pin connected to the pistons; and rods to connect the piston-cranks with the crank of the rotatable shaft, the piston cranks being so located with relation to the pistons that when the pistons are at the end of the compression stroke the pins of the piston cranks, the rotatable shaft and its crank pin will be in a dead-center position but off center with relation to the axes of the pistons, substantially as and for the purpose specified.

8. In an internal combustion engine, the combination of a rotatable shaft having a crank; a pair of piston cylinders located at opposite sides of the shaft, said cylinders comprising drums having removable ends and fuel-intake and exhaust ports in the cylindrical walls; segmental trunk pistons for the respective cylinders having a hub portion with laterally-projecting trunnions whereby they are fulcrumed in the ends of the cylinders and connected to the crank of the shaft, said pistons normally closing the fuel-intake and exhaust ports; removable heads in the cylinders extending between the walls thereof and the hubs of the pistons, said heads with the pistons dividing the piston cylinders into a fuel-pumping chamber and a combustion chamber, the fuel-intake and exhaust ports being so located that when the pistons are at the end of the compression stroke in the combustion chamber the fuel-intake ports will be opened, and when they are at the end of the power stroke the exhaust ports will be opened; by-pass ports in the hubs of the pistons coöperating with the removable heads to open communication between the fuel-pumping and combustion chambers as the pistons begin to uncover the exhaust ports and cut off communication between said chambers when the pistons approach the end of the compression stroke with the fuel-intake port uncovered.

9. In an internal combustion engine, the combination of a rotatable shaft having a crank, a pair of piston cylinders located at

opposite sides of the shaft, said cylinders comprising drums having removable ends and fuel-intake and exhaust ports in the cylindrical wall; segmental trunk pistons for the respective cylinders having a hub portion with laterally-projecting trunnions whereby they are fulcrumed in the removable ends of the cylinders; said pistons normally closing the fuel intake and exhaust ports; a removable head in each cylinder extending between the walls thereof and the hub of the piston, said head with the piston dividing the piston cylinder into a fuel-pumping chamber and a combustion chamber, the fuel-intake and exhaust ports being so located that when the piston is at the end of its compression stroke in the combustion chamber the fuel-intake port will be open, and when it is at the end of its power stroke the exhaust port is open; a by-pass port in the hub of the piston coöperating with the removable head to open communication between the fuel-pumping and combustion chambers as the piston begins to uncover the exhaust port, and cuts off communication between said chambers when the piston is at the end of its compression stroke with the fuel-intake port uncovered; and a deflector secured to the head within the combustion chamber to deflect the fuel coming through the by-pass port to the outer walls of the combustion chamber; cranks fixed to one of the trunnions of the respective pistons outside of the piston cylinders; and connecting rods to connect the said cranks with the crank of the rotatable shaft, whereby to impart rotary motion to said shaft from the oscillations of the pistons.

10. An internal combustion engine, comprising in combination a crank case having a pair of separate fuel chambers; a rotatable shaft journaled in said case; a pair of piston cylinders one at each side of the shaft, the axes of said cylinders being parallel with the axis of the shaft; fuel intake and exhaust ports in the cylinders; oscillating trunk pistons for the respective cylinders controlling the opening and closing of said ports; a head in each cylinder with which the pistons coöperate to divide the cylinders into fuel pumping and combustion chambers with the fuel pumping chamber in each cylinder connected with a fuel chamber in the crank case; and a crank and link connection between said pistons and shaft whereby to impart rotary motion to the shaft from the oscillations of the pistons.

11. In an internal combustion engine, the combination of a rotatable shaft having a crank; a pair of piston chambers comprising cylindrical drums, one located at each side of the shaft and having fuel-intake and exhaust ports; segmental trunk pistons for the respective chambers having trunnions whereby they are fulcrumed to oscillate in

the chambers, said pistons normally closing the fuel-intake and exhaust ports; a head in the respective piston chambers, said heads with the pistons dividing the chambers into fuel-pumping and combustion chambers, the fuel-intake and exhaust ports being so located that when the piston is at the end of its compression stroke in the combustion chamber the fuel-intake port will be uncovered and the exhaust port covered, and when it is at the end of its power stroke the exhaust port will be uncovered and the fuel-intake port covered; a by-pass port in the pistons coöperating with the cylinder heads to open up and cut off communication between the fuel-pumping and combustion chambers; and means to connect the pistons to the crank of the shaft.

12. In an internal combustion engine, the combination of a crank case having a pair of separate fuel chambers; a crank shaft having a crank journaled in said case; piston cylinders comprising drums located at opposite sides of the crank case adjacent to the fuel chambers having fuel-intake ports and exhaust ports; pistons to oscillate in the respective cylinders; a head for each cylinder, said heads with the pistons dividing the cylinders into fuel-pumping chambers communicating with the fuel chambers in the crank case, and a combustion chamber; a by-pass port in the pistons to coöperate with the heads to open and cut off communication with the respective chambers; and connecting rods to connect the pistons with the crank shaft.

13. In an internal combustion engine, the combination of a crank case having a pair of separated fuel chambers; a crank shaft journaled in said case between the said chambers; a pair of piston cylinders comprising drums one at each side of the crank case adjacent to and integral with the fuel chambers with their axes parallel with the axis of the crank shaft; trunk pistons fulcrumed to oscillate in the respective cylinders; a head for each cylinder extending between the walls thereof and the piston, said heads when the pistons are in the cylinders dividing the cylinders into fuel-pumping chambers communicating with the fuel chambers in the crank case, and having a fuel-intake port, and combustion chambers having an exhaust port; a by-pass port in the pistons coöperating with the cylinder heads to open up and cut off communication between the fuel-pumping and combustion chambers during the oscillations of the pistons; cranks fixed to the pistons; and connecting rods to connect the piston cranks with the crank of the crank shaft.

14. In an internal combustion engine, the combination of a rotatable shaft having a crank; a pair of piston chambers comprising cylindrical drums, one located at each side

- of the shaft and having fuel-intake and exhaust ports; segmental trunk pistons for the respective chambers having a hub portion with laterally projecting trunnions whereby they are fulcrumed to oscillate in the chambers; removable heads in the respective piston chambers, said heads with the pistons dividing the chambers into fuel-pumping and combustion chambers, a by-pass port in the hub of the pistons coöperating with the cylinder heads to open up and cut off communication between the fuel-pumping and combustion chambers; means connected to said heads to deflect the fuel coming through the by-pass port to the outer walls of the cylinders; and means to connect the pistons to the crank of the shaft.
15. In an internal combustion engine, the combination of a crank case having a pair of separate fuel compression chambers; a crank shaft having a crank journaled in said case; piston cylinders comprising drums at opposite sides of the crank adjacent to and communicating with the fuel chambers having fuel-intake ports and exhaust ports; removable ends for the cylinders; pistons to oscillate in the respective cylinders having a hub portion with laterally-projecting trunnions whereby the pistons are fulcrumed in the cylinder ends; cranks connected to the respective pistons; a head for each cylinder extending from the walls of the latter to the hub of the pistons, said heads when the pistons are in the cylinders dividing said cylinders into a fuel-pumping chamber and a combustion chamber; a by-pass port in the hubs of the pistons to coöperate with the heads to open and cut off communication with the respective chambers; a plate fixed to the cylinder heads within the combustion chambers to deflect the fuel coming through the by-pass port to the outer walls of the cylinders; and connecting rods to connect the piston cranks with the crank of the crank shaft.
16. A two cycle internal combustion engine, comprising in combination a rotatable shaft; a piston chamber consisting of a cylindrical drum disposed adjacent to and with its axis parallel with the shaft, said drum having fuel-intake and exhaust ports in the cylindrical wall thereof; a fixed head in the cylinder; a trunk piston fulcrumed in the ends of the drum to oscillate therein and in conjunction with the head separating the drum into a fuel-pumping and compression chamber and a combustion chamber; a port in the piston controlled by the head to open and cut off communication between the fuel pumping and combustion chambers at predetermined points in the oscillations of the piston; said piston controlling the opening and closing of the fuel intake and exhaust ports in the drum so that when a charge of fuel has been compressed in the combustion chamber, it will admit fuel through the fuel-intake port into the fuel-pumping chamber where the fuel is compressed during the power stroke, the piston uncovering the exhaust port when it reaches the end of its power stroke and expelling the exhaust through the exhaust port from the head of the piston, and simultaneously with the opening of the exhaust port injecting the compressed charge of fuel from the pumping chamber into the combustion chamber; and a crank and link connection between the piston and shaft whereby to convert the oscillatory movements of the piston into continuous rotary motion of the shaft.
17. In an internal combustion engine, the combination of a single-throw crank-shaft; piston chambers comprising cylindrical drums at opposite sides of and adjacent to said shaft and having fuel-intake and exhaust ports in the cylindrical walls thereof; heads in the respective drums; pistons to oscillate in the respective drums and controlling the opening and closing of the ports; said pistons with the heads separating the drums into fuel-pumping and combustion chambers; means controlled by the pistons to open and cut off communication between the fuel-pumping and combustion chambers; and crank-and-link mechanism to connect the pistons with the shaft to cause the pistons to move at variable angular velocity whereby there will be a slow compression of the fuel and a quick expansion when the fuel is ignited.
18. An internal combustion engine, comprising a case having a central chamber and a pair of adjacent fuel chambers; a shaft having a crank journaled in the central chamber; a pair of cylindrical drums, one at each side of the shaft and connected with the fuel chambers, the axes of said drums being parallel with the axis of the shaft and having fuel-intake and exhaust ports; oscillating pistons for the respective cylinders controlling the opening and closing of the ports; and a crank-and-link connection between said pistons and shaft whereby to impart rotary motion to the shaft from the oscillations of the pistons.
19. In an internal combustion engine, the combination of a rotatable shaft having a crank; a pair of piston cylinders located at opposite sides of the shaft, said cylinders comprising drums having fuel-intake and exhaust ports in the cylindrical walls thereof; segmental trunk pistons for the respective cylinders having a hub portion with laterally-projecting trunnions whereby they are fulcrumed to oscillate in the cylinders; said pistons controlling the fuel-intake and exhaust ports; removable heads in the respective cylinders extending between the walls thereof and the hub of the pistons,

- 5 said heads with the pistons separating the piston cylinders into fuel-pumping and combustion chambers, the fuel-intake and exhaust ports being so located that when the 50
5 pistons are at the end of the compression stroke in the combustion chambers the fuel-intake ports will be open and the exhaust ports closed, and when they are at the end 55
10 of the power stroke the exhaust ports are opened and the intake ports closed; by-pass ports in the hubs of the pistons coöperating with the heads to open communication between the fuel-pumping and combustion chambers as the pistons begin to uncover the 60
15 exhaust ports, and cuts off communication between the said chambers when the pistons are at the end of the compression stroke with the fuel-intake ports uncovered; deflectors secured to the heads within the 65
20 combustion chambers to deflect the fuel coming through the by-pass ports to the outer walls of the combustion chambers; and means to connect the pistons to the crank of the rotatable shaft.
25 20. In an internal combustion engine, the combination of a rotatable shaft; a piston cylinder having fuel intake and exhaust ports; a piston having a hub portion whereby it is fulcrumed to oscillate in the cylinder; and having a crank-and-link connection with the shaft; fixed means in the cylinder coöperating with the piston to separate the cylinders into a fuel pumping and compression chamber with which the fuel-intake 70
30 35 port communicates, and a combustion chamber with which the exhaust port communicates; and a by-pass port in the piston controlled by the latter means to open and cut off communication between the two chambers at predetermined points in the oscillations of the piston.
40 21. In an internal combustion engine, the combination of a rotatable shaft; a piston cylinder comprising a cylindrical drum located adjacent to said shaft with its axis parallel with the axis of the shaft and having fuel-intake and exhaust ports; a seg- 75
45

mental trunk piston having a hub portion whereby it is fulcrumed to oscillate in the cylinder and connected to the shaft; a head in the cylinder extending between the walls thereof and the hub of the piston, said head with the piston separating the cylinder into a fuel pumping and compression chamber with which the fuel-intake port communicates, and a combustion chamber with which the exhaust port communicates; and a by-pass port in the hub of the piston coöperating with the head to open and cut off communication between the two chambers at 80 predetermined points in the oscillation of the piston.

22. In an internal combustion engine, the combination of a rotatable shaft having a crank; a piston cylinder comprising a cylindrical drum located adjacent to said shaft with its axis parallel with the axis of the shaft and having fuel-intake and exhaust ports; a segmental trunk piston having a hub portion whereby it is fulcrumed to oscillate in the cylinder; a head in the cylinder extending between the walls thereof and the hub of the piston, said head with the piston separating the cylinder into a pair of chambers, one constituting a fuel-pumping and compression chamber with which the fuel-intake port communicates, and the other a combustion chamber with which the exhaust port communicates; a resilient spline carried by said head to bear against the hub of the piston and normally sealing the pumping chamber from the combustion chamber; a by-pass port in the hub of the piston coöperating with the head to open up and cut off communication between the two chambers at predetermined points in the oscillations of the piston; and means to connect the piston to the rotatable shaft whereby the oscillations of the piston will impart continuous rotary motion to the shaft.

Corrections in Letters Patent No. 1,113,262.

It is hereby certified that in Letters Patent No. 1,113,262, granted October 13, 1914, upon the application of Willard Irving Twombly, of New York, N. Y., for an improvement in "Internal-Combustion Engines," errors appear in the printed specification requiring correction as follows: Page 4, line 128, for the word "and" read *one*; page 5, line 15, strike out the word "oil"; same page, line 46, for the word "combination" read *combustion*; and that the said Letters Patent should be read with these corrections therein that the same may conform to the record of the case in the Patent Office.

Signed and sealed this 10th day of November, A. D., 1914.

[~~SEAL.~~]

R. F. WHITEHEAD,
Acting Commissioner of Patents.
